(57) **CLAIM**

The ornamental design for a cleaning article, as shown and described.

DESCRIPTION

FIG. 1 is a perspective view of a first embodiment of a cleaning article showing the new design;

FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a perspective view of a second embodiment of a cleaning article showing the new design with an enlargement boundary defined by dash-dot-dash lines;

FIG. 9 is a top view thereof with an enlargement boundary defined by dash-dot-dash lines;

FIG. 10 is a bottom view thereof;

FIG. 11 is a front view thereof;

FIG. 12 is a rear view thereof;

FIG. 13 is a left side view thereof; and,

FIG. 14 is a right side view thereof.

In the drawings, the dash-dot-dash lines represent boundaries of the claim. The portions of the cleaning article in FIGS. 1–14 shown in broken lines are included to show features that form no part of the claimed design.

1 Claim, 7 Drawing Sheets
